UNITED STATES PATENT OFFICE

BENJAMIN W. SNODGRASS, OF DENVER, COLORADO

AUXILIARY UNIT FOR MINING MACHINES

Application filed February 2, 1929. Serial No. 336,932.

This invention relates to auxiliary units or more in particular to a mechanism so designed and constructed as to attach to or connect with mining machines or other power driven apparatus to furnish power to drive coal drills and operate expansion bars adapted for breaking up the coal.

Among the objects of my invention are to provide a novel construction of auxiliary units adapted to take power direct from a drive means on the ordinary mining machine or other prime mover; further to provide a construction adapted to drive or operate simultaneously a plurality of coal drills at any desired angle from the unit, or drive simultaneously a plurality of coal breaking machines or expanding bars; further to provide a novel construction in which the power take-off is practically universal in both planes; i. e. both in the plane of the pivot of the mining machine and any plane perpendicular to it passing through the vertical axis; further to provide a novel construction of mechanism that can be applied to any of the standard short wall coal cutting machines; further to provide a novel construction of clutch mechanism; further to provide a novel construction of maximum simplicity, efficiency, economy and ease of operation; and such further objects, advantages and capabilities as will later more fully appear.

My invention further resides in the combination, construction and arrangement of parts illustrated in the accompanying drawings, and while I have shown therein a preferred embodiment, I desire it to be understood that the same is susceptible of modification and change without departing from the spirit of my invention.

In the drawings:

Fig. 1 is a top plan view of my new and novel construction.

Fig. 2 is a view in vertical cross section taken on the line 2—2 of Fig. 1.

Fig. 3 is a view in perspective of the cam piece.

Fig. 4 is a view in perspective of my novel construction of dental clutch.

Fig. 5 is a fragmentary view in perspective

of the bevel gear and disclosing the novel construction of the hub.

Fig. 6 is a fragmentary view in perspective of the notched hub of the main gear.

Referring more particularly to the drawings, the numeral 1 designates generally the outer casing of a mining machine, the same being provided with an upstanding shaft 2 upon which is mounted a pinion 3. The pinion 3 meshes with and rotates the main gear 4, the pinion 3 causing the main gear 4 to revolve at all times the mining machine or other prime mover is running. The main gear rotates in the casing or pan 5 which is provided with a central raised portion 6 and shaft or boss 7, the side wall 8 of this casing or pan being provided at its upper portion with an annular plate 9.

The main gear 4 is provided with a central upstanding portion 10 provided with a plurality of grooves or notches 11. Mounted inwardly of the raised portion or annular flange 10 of the main gear is a hub 12 of a bevel gear 13. This bevel gear is further provided with an upstanding portion 14 having a plurality of notches or grooves 15 and openings 15a.

A dental clutch 16 is provided with a plurality of teeth 17 having inwardly extending portions 18 and downwardly extending portions 18a, on its under surface, and a pair of follower pins 19 on its upper surface. These follower pins 19 travel in the groove or cam surface 20 of a cam piece 21, this cam piece being adapted to seat within the portion 22 of the dental clutch, whenever the pins 19 ride upon the uppermost portion 23 of the cam surface 20. The clutch or raising cam 21 is adapted to be turned by means of an arm or handle 24, the turning of which is done by the operator by hand.

The dental clutch, bevel gear and main gear are so constructed as to interconnect, the inwardly extending portions 18 of the teeth 17 are adapted to fit into the radial grooves 15, while the downwardly extending portions 18a of the teeth extend through the openings 15a of the bevel gear 12, and fit into notches 11 in the hub of the main gear 4. Thus when the dental clutch, bevel

100

gear 12 and main gear 4 are in the position shown in Fig. 2, the bevel gear and main gear rotate as a unit. Whenever the raising cam is rotated at a 90° angle so that the follower pins rest in the uppermost portion 23 of the cam surface 20, the teeth of the dental clutch clear the notches in both gears, and although the main gear is rotated continuously, the bevel gear 13 does not rotate since 10 it is out of engagement with the main gear.

A bushing 25 is pressed to the hub of the main gear and provides a tight fit between the hub of the main gear and the hub of the bevel gear, although this fit does not provide 15 for rotation of the gears in unison unless they are connected through the medium of the dental clutch. A bushing 26 is pressed to the stub shaft 7 of the casing or machine pan 5, around which the bevel gear 13, dental clutch and clutch cam may be rotated.

The bevel gear 13 meshes with and rotates a plurality of double faced bevel mitre pinions 29, each of which pinions in turn rotate a mitre union pinion 30, the hub of which is 25 provided with a hollow square core 31 adapted to receive the square end of a telescopic shaft, such as from a drill or expanding bar. Each pinion 29 is rotatably mounted upon a sleeve or bushing 32 on the 30 shaft 33. Arms 34 being the inner end of shafts 33, are swingably mounted on the shaft 7 so as to support them on their inner ends. Bearings 35 are mounted on an arcuate bracket or plate 36 connectible with 35 the plate 9 on the top of the casing or machine pan 5. Pins 37 key the shafts 33 to the bearings 35 and prevent rotation of the shafts. Brackets 38 are provided at one end with a bearing 39 for each shaft 33, while 40 the other ends are provided with a bearing 40 encompassing the hub of the pinions 30.

The pan shaft 7 is hollow and provides a lubricant reservoir. The shaft 7 is internally threaded through approximately one-half its length, and is provided with a threaded plug 41 providing means for compensating for any loss in lubricant. By screwing the plug into the shaft 7, the lubricant in the reservoir may at all times be 45 under compression so as to thoroughly lubricate the parts accessible from the reservoir. A tap 42 screws into the lower portion of the casing or pan shaft 7, and allows for ready access to the lubricant reservoir for 55 draining the same, etc. A pipe 43 allows for the ready lubrication of the bearing surface of the main gear 4.

The clutch mechanism is simple and positive in operation. The longer teeth 18^a engage the slots in the hub of the main gear 4, while the shorter teeth 18 engage the slots in the bevel gear 13, the longer teeth passing between the spokes of the bevel gear.

The raising of the clutch proper is done by 60 the cam surface 20 contacting with the fixed

pins 19 acting as cam followers. On the revolution of the cam piece 21 through an arc of 90°, the follower pins 19 will travel up the cam surfaces to the upper position 23 and raising the entire clutch a sufficient distance for lifting the longer teeth 18^a from their positions in the holes or openings 11 in the main gear hub. The bevel gear 13, clutch and the remaining parts actuated by the bevel gear stop rotating, while the main gear and the pinion 3 rotate with the prime mover or driving means, it being understood that such main gear and pinion rotate at all times during the operation of such driving mechanism. Thus the primary function of the clutch is to transmit power from the hub of the main gear to the hub of the bevel gear through the medium of the clutch teeth. All that it takes to stop the bevel gear 13 is for the operator to revolve the cam piece by 70 means of the handle 24 a quarter turn which raises the teeth 18^a from their engagement with the main gear.

The primary purpose of my construction is to drive simultaneously a plurality of coal 90 drills, expanding bars, or the like, at any desired angle from this unit. Although I have shown three bevel mitre pinions and their power transmitting means, it is to be understood that any number may be used as 95 desired. Also these transmitting means may be positioned at any desired angle or position on the plate 9 of the machine pan or casing.

From the above disclosure, it will be seen 100 that I have provided a novel construction of auxiliary units which may be readily and economically connected to any of the present mining machines or other prime movers and which may operate a plurality of mine 105 working tools.

Having thus disclosed the invention, I claim:

1. An auxiliary unit adapted to be connected to a mining machine, comprising a casing having a projecting boss, a driving gear having a hub around said boss, and a driven gear having a hub mounted for rotation within the hub of said driving gear and about 110 said boss.

2. An auxiliary unit adapted to be connected to a mining machine, comprising a casing having a projecting boss, a driving gear having a hub around said boss, a driven gear having a hub mounted for rotation within the hub of said driving gear and about said boss, and a clutch for interconnecting said gears so that the same may rotate together.

3. An auxiliary unit comprising a casing having an upwardly projecting boss, a gear driven by a source of power and projecting through an opening into said casing, a gear in said casing driven by said first gear and having a hub around said boss, and another gear driven by said second gear having a hub 125 130

mounted for rotation within the hub of said second gear and about said boss.

4. An auxiliary unit comprising a casing having an upwardly projecting boss, a gear driven by a source of power and projecting through an opening into said casing, a gear in said casing meshing with said first gear and having a hub around said boss, another gear mounted for rotation within the hub of said second gear and around said boss, and means for interconnecting said last mentioned gear with said second gear.

5. An auxiliary unit adapted to be connected to a mining machine, comprising a casing having a central raised portion, a boss projecting upwardly from said portion, a driving gear having a hub mounted on said portion and about said boss, and a second gear having a hub mounted on said raised portion and around said boss and rotatable within the hub of said driving gear, and means for connecting said gears together.

6. An auxiliary unit adapted to be connected to a mining machine, comprising a casing having an upwardly projecting boss, a driving gear having a hub around said boss, a driven gear having a hub mounted for rotation within the hub of said driving gear and about said boss, and a clutch slidable on said boss provided with teeth for connecting said driving and driven gears.

7. An auxiliary unit adapted to be connected to a mining machine, comprising a casing having an upwardly projecting boss, a driving and a driven gear mounted for rotation about said boss, and a clutch slidable on said boss and adapted to engage said gears whereby said gears are connected together.

8. An auxiliary unit adapted to be connected to a mining machine, comprising a casing having an upwardly projecting boss, a driving and a driven gear mounted for rotation about said boss, a clutch movable on said boss adapted to engage with said gears for connecting them together, and a cam piece mounted on said boss for moving said clutch into and out of engagement with said gears.

9. An auxiliary unit adapted to be connected to a mining machine, comprising a casing having an upwardly projecting boss, a driving and a driven gear mounted for rotation about said boss, a clutch movable on said boss and adapted to engage with said gears for connecting them together, a cam piece mounted on said boss and having cam grooves therein, and means connected to said clutch and engaging in said grooves whereby said clutch is moved into and out of engagement with said gears upon movement of said cam piece.

10. An auxiliary unit adapted to be connected to a mining machine, comprising a casing having an upwardly projecting boss, a driving and driven gear mounted for rotation about said boss, and means driven by said driven gear for operating a mining tool, said

means including a shaft mounted on said casing and having an arm mounted on said boss.

11. An auxiliary unit adapted to be connected to a mining machine, comprising a casing having an upwardly projecting boss, a driving and driven gear mounted for rotation about said boss, and means driven by said driven gear for operating a mining tool, said means including a shaft mounted on said casing and having an arm mounted on said boss, a gear mounted on said shaft and meshing with said driven gear, and a second gear meshing with the gear on said shaft for operating a mining tool.

12. An auxiliary unit adapted to be connected to a mining machine, comprising a casing having an upwardly projecting boss, a driving and driven gear mounted for rotation about said boss, and means driven by said driven gear for operating a mining tool, said means including a shaft mounted on said casing, a gear mounted on said shaft and meshing with said driven gear, a bracket secured to said shaft, and a second gear mounted on said bracket and meshing with the gear on said shaft for operating a mining tool.

13. An auxiliary unit adapted to be connected to a mining machine, comprising a casing having an upwardly projecting boss, a driving and driven gear mounted for rotation about said boss, and means mounted on said casing and driven by said driven gear for operating a mining tool, said means being swingably mounted on said boss.

14. An auxiliary unit adapted to be connected to a mining machine, comprising a casing having a hollow upwardly projecting boss, a driving and driven gear mounted for rotation about said boss, and closure means for said hollow boss for holding a lubricant therein, said boss having openings therethrough for lubricating said gears.

15. An auxiliary unit adapted to be connected to a mining machine, comprising a casing having an upwardly projecting boss, said boss having a longitudinal opening therethrough for retaining a lubricant therein, closure means for said opening, a driving and driven gear mounted for rotation about said boss, said boss having openings therethrough for passage of the lubricant to said gears, one of said closure means being adjustable in said longitudinal opening for keeping said lubricant under pressure.

16. An auxiliary unit adapted to be connected to a mining machine, comprising a casing having a raised portion and an upwardly projecting boss, said boss having a longitudinal opening therethrough for retaining a lubricant therein, closure means for said opening, a driving and driven gear mounted on said portion and about said boss, said boss having openings for passage of the lubricant to said gears.

17. An auxiliary unit adapted to be con-

- nnected to a mining machine, comprising a casing having a raised portion and an upwardly projecting boss, said boss having a longitudinal opening therethrough for holding a lubricant, closure means for said opening, a driving gear having a hub mounted upon said portion and about said boss, and a driven gear having a hub mounted within the hub of said driving gear and around said boss, said boss having openings for passage of the lubricant to the clearance spaces between said gears, the hub of said driven gear and boss, and said gear hubs and raised portion.
18. An auxiliary unit adapted to be connected to a mining machine, comprising a casing having a raised portion and an upwardly projecting boss, said boss having a longitudinal opening therethrough for holding a lubricant, closure means for said opening, a driving gear having a hub mounted upon said portion and about said boss, a driven gear having a hub mounted within the hub of said driving gear and around said boss, said boss having openings for passage of the lubricant to the clearance spaces between said gears, the hub of said driven gear and boss, and said gear hubs and raised portion, the hub of said driving gear having an opening therethrough, and means communicating with said opening for passage of said lubricant to the teeth of said gear.

In witness whereof I hereunto subscribe my name to this specification.

BENJAMIN W. SNODGRASS.
